United States Patent

Des. 236,484

Patented Aug. 26, 1975

236,484

CONTROL AND KEYBOARD UNIT

Richard G. Clayton, Detroit, Mich., assignor to
Burroughs Corporation, Detroit, Mich.

Filed Nov. 2, 1973, Ser. No. 412,260

Term of patent 14 years

Int. Cl. D14—02

U.S. Cl. D26—5 C

The single figure is a front perspective view of a control and keyboard unit showing my new design. The left side of the unit which is not shown is flat and the rear of the unit which is not shown is unornamented.

I claim:

The ornamental design for a control and keyboard unit, as shown and described.
